UNITED STATES PATENT OFFICE.

ELIJAH BAILEY BENHAM, OF NEW LONDON, CONNECTICUT, ASSIGNOR TO THOMAS A. NEVINS, OF EAST ORANGE, NEW JERSEY.

APPARATUS FOR EMPLOYING KEROSENE AND HEAVIER LIQUID FUELS IN INTERNAL-COMBUSTION ENGINES.

1,205,505.

Specification of Letters Patent. Patented Nov. 21, 1916.

Application filed July 9, 1913. Serial No. 778,106.

To all whom it may concern:

Be it known that I, ELIJAH B. BENHAM, a citizen of the United States of America, and a resident of New London, county of New London, and State of Connecticut, have invented certain new and useful Apparatus for Employing Kerosene and Heavier Liquid Fuels in Internal-Combustion Engines, of which the following is a specification.

10 My invention relates to an apparatus for employing kerosene and heavier liquid fuels in internal combustion engines, the invention comprising the novel means hereinafter described, whereby liquid fuel supplied to an internal combustion engine is heated and volatilized and, to a large extent, converted into a fixed gas, by the heat of the combustion of a previous charge and by mixture with a portion of the products of the combustion of such previous charge, such action taking place externally of the engine cylinder, the resulting gases and vapors being then delivered into the engine cylinder.

The engine to be used according to my invention may be an engine of many of the well known types of internal combustion engines, the apparatus required in order that the engine may operate in accordance with my invention being simple and compact and 25 readily applicable to existing engines. By the means hereinafter described I am able to operate ordinary internal combustion engines on kerosene and heavier hydrocarbon oils, with high efficiency, with great flexibility, with substantially perfect combustion, and with entire freedom from formation of carbonaceous and tarry deposits, in the engine cylinder or in other portions of the apparatus.

40 The objects of my invention are to facilitate the operation of internal combustion engines on kerosene and heavier oils, to provide for that purpose simple apparatus, easily adjusted and operated and readily applicable to engines of well known existing types, to avoid formation of deposits in the engine cylinder, and in other parts of the apparatus, to secure perfect combustion and freedom from smoke and odors, and to obtain high efficiency of operation.

I will now proceed to describe my invention with reference to the accompanying drawings, and will then point out the novel features in claims.

55 In the drawings: Figure 1 shows an axial

section of a typical two cycle internal combustion engine, provided with my improved means for the conversion of kerosene and heavier oils into vapor and gas. Fig. 2 shows a similar section of a typical four-cycle engine likewise provided with my improved means for the conversion of oils into vapor and gas. Fig. 3 is a detail section of a portion of an engine cylinder, showing the said oil conversion apparatus introduced into said cylinder horizontally, instead of vertically as in Figs. 1 and 2. Fig. 4 is a detail axial section, on a larger scale than Figs. 1 and 2, of an engine cylinder and of my oil vaporizing device in place in said cylinder. Fig. 5 shows a transverse section of the oil vaporizing device on the line $\alpha-\alpha$ of Fig. 4. Fig. 6 is a view similar to Fig. 4, but illustrating the alternative construction of the vaporizing device. Fig. 7 is a detail axial section of a further alternative form of the vaporizing device.

Referring now to the accompanying drawings, and at first to Figs. 1 and 4, 1 designates the usual water cooled cylinder of a two-cycle internal combustion engine, 2 the head of such cylinder, shown in this case as removable, though the removability of the head is immaterial, 3 the usual jacket space for the circulation of the cooling water, 4 the usual exhaust port of a two cycle engine, 5 the usual transfer port of a two cycle engine, leading from the crank case or other preliminary compression chamber into the engine cylinder at a point where such port will be uncovered by the engine piston near the lower end of the stroke of that piston; and 6 designates the engine piston provided with the usual deflector 7.

8 designates the gas making device itself, such device comprising a shell 9 fitted into a suitable aperture in the engine cylinder and projecting into said cylinder a suitable distance. The upper end of this shell 9 is closed by a bonnet 10 screwing into the upper end of said shell and provided with a baffle tube 11 extending through the shell 9 to near the other end of that shell; the tube 11 being spaced away somewhat from the inner surface of the shell 9. From the other end of the shell 9 a tube 12 projects into the shell 9 and within but spaced away from the tube 11. The tube 12 is screw-threaded into the corresponding end of the shell 9. The inner end of the tube 12 is closed, except

for a valve-seated port 13, and a needle valve 14, mounted in the bonnet 10, controls escape through this port 13. Said needle valve is provided with a recurved flange 15 which deflects into the space between tubes 12 and 11, gases escaping from the engine cylinder through valve port 13.

The bonnet 10 is provided, on its inner face, with an annular groove 16, and the outer face of the shell 9 is provided with a corresponding registering groove 17, and with a fuel-inlet duct 18 to which a fuel supply pipe 19 connects. The bonnet 10 is also provided with a valve-seated port 20 leading to a space 21 connected, by duct 22, to the interior of tube 11, above the needle valve 14; and a check valve 23 is provided for closing the port 20. The lift of this check valve 23 is regulable by means of a screw 24, and if said screw be turned down sufficiently, the check valve may be prevented altogether from opening, the screw 24 and check valve 23 thereby forming means for cutting off the supply of fuel, when desired, as well as for regulating the fuel supply.

A pipe 25 leads from the space between shell 9 and tube 11 to the transfer port 5 of the engine. The engine is provided, commonly, as is usual, with a priming cup 26, which may be used for the supply to the engine cylinder, when starting, of a small quantity of highly volatile fuel, such as gasoline.

The operation of the device is as follows: Suppose the engine piston 6 to be at about the bottom of its stroke, exhaust port 4 and transfer port 5 being open, the products of combustion of a previous charge flowing out through the port 4 and air from the primary compression space or crank case 27 of the engine flowing into the engine cylinder through transfer port 5, gas and vapor produced as hereinafter described also flowing through pipe 25 into transfer port 5 and thence into the cylinder; as the piston 6 rises, ports 4 and 5 are closed and the charge of mingled air and combustible so introduced into the engine cylinder are compressed, a portion of the charge so compressed passing up through tube 12 and valve 13 and thence through the tortuous passage between tubes 12 and 11 and between tube 11 and shell 9 into pipe 25; but the escape through valve port 13 is too small to permit any considerable portion of the charge escaping from the engine cylinder in this way, the compression of the charge in the engine cylinder to the desired extent not being substantially interfered with. The portion of the charge so escaping through the valve port 13 and thence through the space between tubes 12 and 11 is sufficient, however, to induce a flow of liquid fuel from feed pipe 19 and inlet duct 18

past the valve 23 and through duct 22 into the space above the cap 15 of the needle valve 14; such flow being regulated by the valve 23, for since the lift of such valve is regulable by means of the screw 24, said valve 23 may throttle the inflow of the fuel to any desired extent. The entire structure comprising shell 9 and tubes 11 and 12 has been highly heated by the combustion of the previous charge in the engine cylinder, and hence the oil so admitted through duct 22 into the space between tubes 12 and 11 is quickly volatilized and even converted, in large measure, into fixed gas. Such gas and vapor pass through the tortuous passage between tubes 12 and 11 and between tube 11 and shell 9 into the pipe 25 and transfer port 5. This gas making operation continues during the up-stroke of the piston.

At a suitable point in the upstroke of the piston or in the ensuing down-stroke the charge is ignited by means of the usual ignition device 28 of the engine, and combustion and expansion of the charge take place in the engine cylinder, the piston moving downward and, of course, compression of air in the crank case or primary explosion of the engine taking place in the ordinary manner. During this expansion stroke, a portion of the flaming gases or products of combustion of the charge expanding in such engine cylinder passes up through the tube 9 and port 13, inducing further flow of fuel into the gas making device, which further fuel is converted into gas and vapor in the same manner. When the piston nears the lower end of its stroke it uncovers exhaust port 4, and shortly thereafter, transfer port 5; the expanded gases exhausting through port 4 when said port is opened, and combustible vapor and gas from pipe 25 and compressed air from transfer port 5, passing into the engine cylinder when said port 5 is opened by the piston. This completes the cycle of operations, and a new cycle of operations begins.

In starting the engine, a priming charge of volatile liquid fuel is introduced through the priming cup 26 in the ordinary manner. I have found that the engine starts readily with the introduction of one priming charge only and its ignition. I have found, in actual test of the gas making device herein illustrated and described, that the engine operates smoothly and with great flexibility and without smoke and without formation of carbon or tarry deposits or the like in the gas making device itself or in the engine cylinder. Analysis of the gas drawn from the pipe 25, for purpose of test, has shown the following composition: CO_2 , 8.8%; illuminants, 1.6; O_2 , 0.6; CO , 3.6; CH_4 , 9.4; H_2 , 0; N_2 , 76—giving a B. T. U. value of about 145.

It is probable that the gas varies in com-

position somewhat, with varying oils and with other varying conditions; but I have found that the engine is able to carry practically as high a load, when operated with this gas making device, as when operated on gasoline, and that the fuel consumption is no greater than when the engine is operated upon gasoline.

In Fig. 4 I have indicated means for applying my improved gas making device to an already existing engine cylinder; to this end a hole of suitable size is bored in the engine cylinder or cylinder head at a suitable point, and an annular plug of cement 29 is formed around this hole, to prevent the escape of cooling water, a bushing 30 being introduced into this hole so formed in the engine cylinder and being held in place by a nut 31. The shell 9 of the gas making device 8 is then screwed into this bushing 30. A suitable hole is also bored in the cylinder wall, over the transfer port, and the pipe 25 connected to such hole and to the gas making device, as shown in the drawings.

I have found that the bushing 30 and the cement plug 29 effectively close the water jacket, so that no leakage of water occurs. In the case of engines constructed to employ this gas making device, the use of the cement plug 29 and bushing 30 is of course unnecessary, the shell 9 screwing directly into a suitable hole formed in the engine cylinder, as illustrated in Fig. 6. The particular position of the gas making device in the engine cylinder is not important, as I have found that such gas making device works effectively in a horizontal position or in an inclined position, or even in an inverted position. In Fig. 3 I show said gas making device inserted into the engine cylinder through the side of the cylinder instead of through the head as in Figs. 1, 4 and 6.

I deem it desirable to employ porous material within the gas making device to control and modify the gas formation, as set forth particularly in my U. S. Patents Nos. 920,903, dated May 11, 1909, and 1,000,768, dated August 18, 1911. In Fig. 6 I have indicated one such layer of porous material 32 in the space between tube 11 and shell 9, and in Fig. 7 I have indicated other layers of porous material, 33, in the space between tubes 11 and 12.

My invention is not limited to use with engines of the two cycle type, but is equally applicable to use with four cycle engines, in which latter case the pipe 25 may be connected to the mixing valve 34 or other intake device of the engine as illustrated in Fig. 2.

What I claim is:

1. The combination, with an internal combustion engine having a cylinder, of a chamber so situated within the combustion space of such cylinder as to be surrounded and heated by the hot gases of such combustion

space during the combustion period therein, such chamber provided with fuel admission means, with a discharge outlet external to said cylinder, and with means for the projection of gas under pressure from such engine cylinder through said chamber to said outlet, and a duct connecting the said outlet to the fuel inlet connection of the engine.

2. The combination, with an internal combustion engine having a cylinder, of a chamber seated in an aperture of said cylinder and projecting into the combustion space of such cylinder, and arranged to be heated by combustion within said combustion space, said chamber provided with a fuel inlet and with an outlet connection, the latter external to said engine cylinder, and with means for the projection of gas under pressure from said cylinder through said chamber to said outlet, and a duct connecting the said outlet to the fuel intake of the engine.

3. The combination, with an internal combustion engine having a cylinder, of a chamber so situated within the combustion space of said cylinder as to be heated by combustion within said space, said chamber provided with a fuel inlet connection and with a discharge connection, a baffle within said chamber forming a tortuous open passage between said fuel inlet and said outlet, means for projecting gas under pressure from said cylinder along said baffle in the direction of flow of the fuel from said inlet to said outlet, and a duct connecting said outlet to the fuel intake of the engine.

4. The combination, with an internal combustion engine having a cylinder, of a chamber seated in an aperture in said cylinder and projecting into the combustion space of said cylinder, said chamber provided with a fuel inlet and with an outlet, a baffle in said chamber between said fuel inlet and outlet, a tube projecting into said chamber from the engine cylinder, and open at its cylinder end and provided at its opposite end with a port, means for deflecting gas flowing from said tube into said chamber along said baffle and in the direction of the flow of fuel from said inlet to said outlet and a duct connecting said outlet to the fuel intake of the engine.

5. The combination, with an internal combustion engine having a cylinder, of a chamber seated in an aperture of said cylinder and projecting into the combustion space of said cylinder, a tube extending from the so-projecting end of said chamber into the chamber, said tube open at its engine-cylinder end, and provided at its other end with a valve-port, a valve regulating flow through said port, said chamber provided with a fuel inlet and with an outlet connection, a baffle within said chamber and surrounding said tube and spaced away from both said tube and said chamber, and form-

- ing, with the tube and chamber, a tortuous passage for the flow of fluid from said inlet to said outlet, means for causing gas under pressure passing from said cylinder through 5 said tube and port to flow through said tortuous passage in the direction of flow of fuel from said inlet to said outlet, and a duct connecting said outlet to the fuel intake of the engine.
- 10 6. The combination, with the cylinder of an internal combustion engine, of a fuel heating device projecting through an aperture of said cylinder into the combustion space of said cylinder, and provided with 15 a fuel inlet and with an outlet connection and with means converting the interior of said chamber into a tortuous passage leading from said inlet to said outlet connection, means for projecting gas under pressure 20 from said engine cylinder through said tortuous passage from a point near said inlet to said outlet connection, and a duct connecting said outlet connection to the fuel intake of the engine cylinder.
- 25 7. A fuel heating device for internal combustion engines comprising a chamber adapted for location within the combustion space of an internal combustion engine, and provided near one end, with an outlet connection, the baffle tube within said chamber spaced away from the walls thereof and converting the interior of said chamber into a tortuous passage leading from said inlet to said outlet, and means for projecting gas 30 under pressure through said tortuous passage in the direction of flow of fuel from said inlet to said outlet, both said outlet connection and the inlet to the means for projecting gas as specified being located to 35 be external to the engine cylinder when the fuel heating device is attached to an engine cylinder.
8. A fuel heating device for internal combustion engines, comprising in combination 45 a chamber adapted for location within the combustion space of an internal combustion engine and having near one end a fuel inlet and an outlet connection, a baffle within said chamber converting the interior 50 of said chamber into a tortuous passage leading from said inlet to said outlet, a tube extending from the other end of said chamber into said chamber, said tube open at its outer end and provided with a port 55 through which gas under pressure may flow into said passage.
9. A fuel heating device for internal combustion engines, comprising in combination 60 a chamber adapted for location within the combustion space of an internal combustion engine and having near one end a fuel inlet and an outlet connection, a baffle within said chamber converting the interior 65 of said chamber into a tortuous passage leading from said inlet to said outlet, a tube
- extending from the other end of said chamber into said chamber, said tube open at its outer end and provided with a port through which gas under pressure may flow into said passage, and means for causing 70 gas entering said port to flow through said tortuous passage in the direction of flow of fuel from said inlet to said outlet.
10. A fuel heating device for internal combustion engines, comprising in combination 75 a chamber adapted for location within the combustion space of an internal combustion engine and having within it a return bend fuel passage together with a fuel inlet and an outlet for said passage, and means for projecting gas under pressure through said tortuous passage in the direction of said outlet.
11. A fuel heating device for internal combustion engines, comprising a chamber 80 adapted for location within the combustion space of an internal combustion engine and having within it a return bend fuel passage and a fuel inlet and an outlet for said passage, and means for projecting gas under 85 pressure from an engine cylinder to which said fuel heating device may be connected, through said passage in the direction of the outlet, comprising a port in a portion of said chamber which is within such combustion chamber when such fuel heating device is in place in an engine cylinder.
12. A fuel heating device for internal combustion engines, comprising in combination 90 a chamber adapted for location within the combustion space of an internal combustion engine, and having a fuel passage within it and a fuel inlet and an outlet for said passage, a tube projecting into said chamber from a portion of the chamber 95 which is within the engine cylinder when such fuel heating device is in place in an engine cylinder, said tube provided at a point well within said chamber with a port adapted for connecting the engine cylinder to the interior of said chamber.
13. A fuel heating device for internal combustion engines, comprising in combination 100 a chamber adapted for location within the combustion space of an internal combustion engine, and having a fuel passage within it and a fuel inlet and an outlet for said passage, a tube projecting into said chamber from a portion of the chamber 105 which is within the engine cylinder when such fuel heating device is in place in an engine cylinder, said tube provided at a point well within said chamber with a port adapted for connecting the engine cylinder to the interior of said chamber.
14. A fuel heating device for internal combustion engines, comprising in combination 110 a chamber adapted for location within the combustion space of an internal combustion engine, and having a fuel passage within it and a fuel inlet and an outlet for said passage, a tube projecting into said chamber from a portion of the chamber 115 which is within the engine cylinder when such fuel heating device is in place in an engine cylinder, said tube provided at a point well within said chamber with a port adapted for connecting the engine cylinder to the interior of said chamber, and a valve 120 controlling flow through such port.
15. A fuel heating device for internal combustion engines, comprising in combination 125 a chamber adapted for location within the combustion space of an internal combustion engine, and having a fuel passage within it and a fuel inlet and an outlet for said passage, a tube projecting into said chamber from a portion of the chamber 130 which is within the engine cylinder when such fuel heating device is in place in an engine cylinder, said tube provided at a point well within said chamber with a port adapted for connecting the engine cylinder to the interior of said chamber, and a valve controlling flow through such port.

1. A combustion engine, and having a fuel passage within it and a fuel inlet and an outlet for said passage, a tube projecting into said chamber from a portion of the chamber 5 which is within the engine cylinder when such fuel heating device is in place in an engine cylinder, said tube provided at a point well within said chamber with a port adapted for connecting the engine cylinder 10 to the interior of said chamber, and a valve controlling flow through such port and provided with a deflector adapted to deflect gas passing through such port and to cause such gas to flow through such chamber 15 in the direction of flow of fuel from the fuel inlet to the outlet of such chamber.
2. A fuel heating device for internal combustion engines comprising in combination a chamber adapted for location within the combustion space of an internal combustion engine and having a fuel inlet and an outlet and a tubular baffle between said inlet and outlet dividing the interior of said chamber into a tortuous passage leading 25 from said fuel inlet to said outlet, a tube projecting into said chamber from a portion of said chamber which is within the engine cylinder when said fuel heating device is in place in an engine cylinder, said tube provided at a point well within said chamber with a port leading into said tortuous passage, and a valve regulating flow through 30 said port, and provided with a deflector arranged to deflect gases passing from the engine cylinder through said port through said tortuous passage in the direction of flow of the fuel from the fuel inlet to the outlet of such passage.
3. The combination, with an internal combustion engine having an engine cylinder and compression chamber and means for supplying compressed air to said cylinder comprising a transfer port leading from such compression chamber to the engine cylinder, of a fuel heating device comprising a chamber located within the combustion space of said engine cylinder and having a fuel inlet and an outlet both external to said engine cylinder, and a duct connecting the outlet of said chamber to said transfer port.
4. The combination, with an internal combustion engine having an engine cylinder and compression chamber and means for supplying compressed air to said cylinder comprising a transfer port leading from such compression chamber to the engine cylinder, of a fuel heating device comprising a chamber located within the combustion space of said engine cylinder and having a fuel inlet and an outlet both external to said engine cylinder and means for permitting gas under pressure to flow from said engine cylinder into said chamber, and a duct connecting the outlet of said chamber to said transfer port.
5. A fuel heating attachment for internal combustion engines, comprising a chamber adapted to be connected to a suitable port of an engine cylinder for circulation of hot gas from such cylinder in heat exchanging relation to said chamber, said chamber provided with a fuel inlet and a fuel outlet, each in a portion of the chamber which is arranged to be external to the engine cylinder, said chamber provided with a port leading from a portion of the wall of such chamber which is within the engine cylinder when the device is in use, into the interior of said chamber, through which port gas under pressure may pass from such engine cylinder into such chamber.
6. A fuel heating attachment for internal combustion engines, comprising a chamber adapted to be connected to a suitable port of an engine cylinder for circulation of hot gas from such cylinder in heat exchanging relation to said chamber, said chamber provided with a fuel inlet and a fuel outlet, each in a portion of the chamber which is arranged to be external to the engine cylinder, said chamber provided with a port for the passage of gas from the engine cylinder into such chamber in the direction of flow through the chamber toward the outlet thereof, such port being located in a portion of such chamber which is within the engine cylinder when the device is in use.
7. A fuel heating attachment for internal combustion engines, comprising a chamber adapted to be connected to a suitable port of an engine cylinder, for circulation of hot gas from said cylinder in heat exchanging relation to said chamber, said chamber provided with a tube projecting from the end of such chamber which will be nearest the engine cylinder into the chamber, such tube being open at its outer end and provided at its inner end with a port connecting with the interior of such chamber.
8. A fuel heating attachment for internal combustion engines, comprising a chamber adapted to be connected to a suitable port of an engine cylinder, for circulation of hot gas from said cylinder in heat exchanging relation to said chamber, said chamber provided with a tube projecting from the end of such chamber which will be nearest the engine cylinder into the chamber, such tube being open at its outer end and provided at its inner end with a port connecting with the interior of such chamber, said chamber further provided with means for deflecting gas flowing through such port and causing such gas to flow through the chamber toward the outlet thereof.
9. A fuel heating attachment for internal combustion engines, comprising a chamber adapted to be connected to a suitable port of an engine cylinder, for circulation of hot gas from said cylinder in heat exchanging relation to said chamber, said chamber provided with a tube projecting from the end of such chamber which will be nearest the engine cylinder into the chamber, such tube being open at its outer end and provided at its inner end with a port connecting with the interior of such chamber, said chamber further provided with means for deflecting gas flowing through such port and causing such gas to flow through the chamber toward the outlet thereof.

6
of hot gas from such cylinder in heat ex-
changing relation to such chamber, said
chamber provided with a fuel inlet and a
fuel outlet each in a portion of the cham-
ber which is arranged to be external to the
engine cylinder, and with an open valveless
passage connecting said inlet and outlet, and
further provided with a check valve for the
said inlet which check valve is arranged to
10 be opened by suction produced within the
chamber.

23. A fuel heating attachment for inter-
nal combustion engines, comprising a cham-
ber adapted for insertion through a suitable
15 port of an engine cylinder, such chamber
provided at an intermediate point with
means for forming a joint with the wall of
the engine cylinder, whereby a portion of
the chamber may project into the engine
20 cylinder and a portion of the chamber may
remain external to the engine cylinder, said
chamber provided, in such external portion,
with a fuel inlet and with a fuel outlet,
both connecting with the interior of such
25 chamber, and being also provided with a
port, located in a portion of such chamber
which is within the engine cylinder when
the device is in use, which port is adapted
for the flow of gas from said cylinder into
30 such chamber.

24. A fuel heating attachment for inter-
nal combustion engines, comprising a cham-
ber adapted for insertion through a suitable
35 port of an engine cylinder, such chamber
provided at an intermediate point with
means for forming a joint with the wall of
the engine cylinder, whereby a portion of
the chamber may project into the engine
40 cylinder and a portion of the chamber may
remain external to the engine cylinder, said
chamber provided, in such external portion,
with a fuel inlet and with a fuel outlet, both
connecting with the interior of such cham-
45 ber, said chamber further provided with
means located in a portion of such chamber
which is within the engine cylinder when
the device is in use, for the projection of
gas under pressure from such engine cylin-
50 der into the interior of such chamber and
toward the outlet thereof.

25. A fuel heating attachment for inter-
nal combustion engines, comprising a cham-
ber adapted for connection to a suitable port
of an engine cylinder, for circulation of hot
55 gas from such cylinder into heat exchang-
ing relation to such chamber, said chamber
provided with a fuel inlet having a check
valve, and with a fuel outlet, and with an
open valveless return bend passage connect-
60 ing said inlet and outlet, said chamber fur-
ther provided with means for the projec-
tion of gas under pressure, from an engine
cylinder to which such chamber may be con-

nected, through such passage toward said
outlet.

26. A fuel heating attachment for inter-
nal combustion engines, comprising a cham-
ber adapted for connection to a suitable port
of an engine cylinder, for circulation of hot
gas from such cylinder into heat exchang-
70 ing relation to such chamber, said chamber
provided with a fuel inlet having a check
valve and with a fuel outlet, and with an
open valveless return bend passage connect-
ing said inlet and outlet, said chamber fur-
75 ther provided with means for the projec-
tion of gas under pressure, from an engine
cylinder to which such chamber may be con-
nected, through such passage toward said
outlet, the device being devoid of automatic
80 valves other than such check valve.

27. A fuel heating attachment for inter-
nal combustion engines, comprising a cham-
ber arranged to be heated by hot gases from
85 the cylinder of an engine to which the de-
vice may be attached, such chamber pro-
vided with a fuel inlet and a fuel outlet, and
a passage connecting the same, and further
provided with means for inducing flow of
90 fuel through such passage by the inductive
action of gas under pressure flowing
through such passage.

28. A fuel heating attachment for inter-
nal combustion engines, comprising a cham-
ber arranged to be heated by hot gases from
95 the cylinder of an engine to which the de-
vice may be attached, such chamber pro-
vided with a fuel inlet and a fuel outlet,
and a passage connecting the same, and fur-
ther provided with means for inducing flow 100
of fuel through such passage by the induc-
tive action of gas under pressure flowing
through such passage, said chamber further
provided with a valve for said inlet.

29. A fuel heating attachment for inter-
105 nal combustion engines, comprising a cham-
ber arranged to be heated by hot gases from
the cylinder of an engine to which the de-
vice may be attached, such chamber pro-
vided with a fuel inlet and a fuel outlet,
110 and a passage connecting the same, and fur-
ther provided with means for inducing flow
of fuel through such passage by the induc-
tive action of gas under pressure flowing
through such passage, said chamber further
115 provided with a valve for said inlet, such
valve arranged to be opened by suction pro-
duced by gas flowing through such passage.

In testimony, whereof I have signed this
specification in the presence of two sub- 120
scribing witnesses.

ELIJAH BAILEY BENHAM.
